SAFETY RAZOR SET CASE

Charles L. Metzler, Palisades Park, N. J., and
William H. Dennerlein, Bethpage, N. Y.

Application June 6, 1958, Serial No. 51,223

Term of patent 14 years

(Cl. D58—12)

Fig. 1

Fig. 2

Fig. 3

Fig. 4

Fig. 1 is a front perspective view of a safety razor set case embodying our new design;

Fig. 2 is a front perspective view thereof, in open position;

Fig. 3 is a top plan view thereof; and

Fig. 4 is a back perspective view thereof.

This application is a continuation-in-part of our co-pending application, Serial No. D. 48,360, filed Nov. 7, 1957, now abandoned.

We claim:

The ornamental design for a safety razor set case, substantially as shown.
